UNITED STATES PATENT OFFICE.

BRUCE A. SHAW, OF OAK PARK, ILLINOIS.

PISTON FOR PNEUMATIC SMOKERS.

1,112,334.

Specification of Letters Patent. Patented Sept. 29, 1914.

Application filed February 2, 1912. Serial No. 674,970.

To all whom it may concern:

Be it known that I, BRUCE A. SHAW, a citizen of the United States, residing at Oak Park, in the county of Cook and State of Illinois, have invented new and useful Improvements in Pistons for Pneumatic Smokers, of which the following is a specification.

The invention has for its general object a hunter's or sportsman's smoking device which is so constructed as to inject or force a volume of dense smoke into the den of an animal and against the usual dead air pressure of the den, thus reducing to a minimum the time and effort heretofore required in the 15 operation of what is known as "smoking out" animals; and to this end the invention consists in certain improved constructions, arrangements and combinations of devices which will be fully described hereinafter 20 and then pointed out in the claims.

Other objects will appear and be better understood from that embodiment of my invention of which the following is a specification, reference being had to the accompanying 25 drawings forming a part hereof, in which;

Figure 1 is a perspective of the device with a part broken away. Fig. 2 is a view looking from the rear of the device with the 30 piston removed. Fig. 3 is a detail partly in section and elevation of the plunger showing by full lines the positions of the parts during the inward movement of the plunger and by dotted lines the positions of the parts 35 during the outward movement of the plunger. Fig. 4 is a detail of one of the smoke generating cartridges preferably employed in connection with my smoker.

The body 5 of the smoker may be formed 40 of any suitable material such as metal, and may be of any desired contour such as cylindrical. The forward end 6 of the body has a contracted spout or nozzle 7 which is adapted for insertion into the mouth of the 45 den of the animal or for connection to a hose or length of pipe (not shown) when the den is relatively long or deep.

The body 5 is formed in the end portion adjacent to the nozzle 7 with a smoke or gas 50 generating chamber 8 which is adapted to contain any substance found suitable for generating smoke or the like, such as a cartridge 9 shown in detail in Fig. 4, which is made up of rags coated with a compound 55 of sulfur and charcoal. The chamber 8 communicates at one end with an air blast

compartment 10 which is also formed within the body 5 and located in the end portion thereof remote from the forward end 6. This air blast compartment 10 contains an 60 element of suitable construction such as a piston or plunger 11, which operates when moved in one direction to force the air from the compartment and into the smoke chamber 8, where, if the cartridge 9 is ignited, 65 the air moving through the smoke chamber and toward the nozzle will commingle with and carry the smoke through the nozzle 7. The piston or plunger 11 is provided with a packing ring 12 which insures against the 70 escape of air around the periphery of the plunger when the plunger is forced inwardly so that if the inward movement of the plunger be relatively rapid the velocity of the 75 mixture of air and smoke as it enters the nozzle, will be increased thereby so that the pressure ordinarily required to produce a quick inward movement of the piston will be sufficient to cause a relatively long jet or stream of smoke to issue from the nozzle 7. 80

The piston or plunger 11 is hollow and has a valve 13 which when the piston is moving inwardly, seals the opening 14 in one end thereof so as to prevent the passage of air therethrough, but when the piston is retracted or moved in the opposite direction the valve unseals the opening 14, and the lugs or teeth 15 on the valve by abutting the adjacent end of the piston, prevent the valve from sealing the opening 16 and consequently and by reason of permitting air to 90 pass through the openings 14 and 16 and around the valve, or in other words through the piston, insure against the forming of a partial vacuum in the smoke chamber and 95 air compartment and thus the withdrawing of the smoke from the place into which it has been injected.

The rod 17 which is suitably connected to the valve 13 such as by clamp nuts 18—18 100 extends through the cover 19 which is removably secured to the rear end of the body 5 and held against accidental displacement therefrom by a suitable fastening device such as a stud 20, which interlocks with a 105 bayonet slot 21 in the cover 19. The handle 22 which is formed with or otherwise suitably connected to the outer end of the rod affords a grip for the hand of the operator which operates the piston or plunger. The 110 body portion 24 of the cover 19 which forms a stop for the inward movement of the

handle 22, has one or more openings 25 which form passages for any air which might be moved toward the head or cover during the outward movement of the piston 5 and, thus insure against compression by such outward movement and warrant unhampered outward movement of the piston, barring, of course, such resistance as is offered to this outward movement by the friction of the periphery of the piston and the wall of the compartment 10.

A screen 26 at the inner end of the nozzle 7 permits of the passage of the mixed gases therethrough, but prevents the falling of the 15 gas or smoke generating substance out of the chamber when the body extends vertically downward. The apertured wall 27 between the chamber 8 and air compartment 10 also prevents the falling of the cartridge 20 into the said compartment when the body is pointed vertically upward.

Although I have shown and described one embodiment of my invention it is to be understood that I am not to be limited to the 25 specific arrangement and construction of parts since various changes may be made, within the scope of the appended claims without departing from the spirit or sacrificing any of the advantages of the invention.

What I claim as new is:

1. A plunger for pneumatic smokers including a hollow casing comprising spaced parallel walls, each formed with an opening, 35 a valve strip freely movable between the

walls and of materially less diameter than the similar dimension of the casing, and a plunger operating rod connected directly to the valve strip, said valve strip being formed with projections arranged at an angle to one surface adapted in movement of the strip in one direction to engage the inner surface of one of the walls of the casing to maintain the valve strip in spaced relation to such wall, said casing being formed for 45 the reception of edge packing.

2. A plunger for pneumatic smokers including a hollow casing comprising spaced parallel walls, each formed with an opening, a valve strip freely movable between the 50 walls and of materially less diameter than the similar dimension of the casing, and a plunger operating rod connected directly to the valve strip, said valve strip being formed with projections arranged at an angle to one surface adapted in movement of the strip in one direction to engage the inner surface of one of the walls of the casing to maintain the valve strip in spaced relation to such wall, said valve strip serving as a means for connecting the casing and plunger rod to permit said rod to move the casing subsequent to the limit movement of the valve strip in either direction.

In testimony whereof I affix my signature 65 in presence of two witnesses.

BRUCE A. SHAW.
